INVENTOR:

ADOLF SELLIN

BY: *Frank Oldenmull*

ATTORNEY.

UNITED STATES PATENT OFFICE.

ADOLF SELLIN, OF STUTTGART, GERMANY.

OPERATING MECHANISM FOR VALVELESS PLUNGER-PUMPS.

1,277,650.

Specification of Letters Patent.

Patented Sept. 3, 1918.

Application filed June 9, 1915. Serial No. 33,146.

To all whom it may concern:

Be it known that I, ADOLF SELLIN, a citizen of the German Empire, residing at Stuttgart, in the Kingdom of Wurtemberg, Germany, have invented certain new and useful Improvements in Operating Mechanism for Valveless Plunger-Pumps; and I do hereby declare the following to be a full, clear, and exact description of the invention, such as will enable others skilled in the art to which it appertains to make and use the same.

This invention relates to improvements in operating mechanism for valveless plunger pumps, and more particularly for pumps for forced feed lubrication.

The invention illustrated in the drawings shows an arrangement designed for supplying lubricant to four places, but it should be understood that it can be applied to any number of places by simply arranging a similar construction on the opposite side of the worm wheel to that shown in the drawings.

In the drawings, Figure 1 is a side elevation of a device comprising a plurality of pumps according to the present invention.

Fig. 2 shows a transverse vertical sectional view, partly in elevation, taken on one of the pumps.

Fig. 3 is a similar view with the movable parts in a different position.

Fig. 4 is a plan showing the parts in one position.

Fig. 5 is a plan of part of the device showing the parts in another position.

Fig. 6 is a plan of a detail.

Figs. 7, 8, 9, and 10 show different relative positions of some of the movable parts.

Fig. 11 is a plan of a detail.

Referring more particularly to Figs. 1, 2 and 3, in the cylinders 1 are disposed plungers 2 provided with suitable ports 3 and 4. A cam 5 fixed on the worm wheel 6 engages the yoke 7 in a square aperture 8 therein.

The plungers 2 are held in engagement with the yoke by means of nuts 9 and 10 in such manner that the said plungers may be partially rotated or turned by means of a wrist pin 11 mounted on the plate 12 on the plungers and engaging in a recess 13 in the said yoke. The plungers 2 are also provided with a longitudinally extending channel 20 communicating with the cylinder through the bottom of said plunger. Transverse

channels 21 and 22 are also provided in said plungers and extend from the center channel

20 to communicate, at different periods of the stroke, with, respectively, the inlet 14 and the outlet 15 through, respectively, ports 3 and 4.

Owing to the peculiar form of the cam 5, which engages in the square aperture 8 of the yoke 7, the said yoke is given, not a uniform circular movement, but an intermittent four-motion movement, first to the left (Fig. 7), then upward (Fig. 8), thence to the right (Fig. 9) and finally downward (Fig. 10). In order that the yoke may be moved laterally, as required in the four-motion movement, elongated recesses 16 are provided therein, as shown in Fig. 6.

The arrangement of the parts is such that the operating yoke, when moving up or down, does directly reciprocate the plungers for the suction and pressure periods, and then moving sidewise, in either direction, merely causes the plate 12 and wrist pin 11 to turn the plungers to suitable positions in order to register with the inlet and outlet. All movements of the yoke are directly contributed thereto by the cam, 5.

The operation of the device is as follows:

The worm wheel 6 being revolved also turns the cam 5, and this cam, through engagement with the square aperture 8, imparts an intermittent four-motion movement to the yoke 7. During such four-motion movement, the plunger being in the position shown in Fig. 2, the cam 5 engaging the yoke through the square aperture forces the yoke from the position of Fig. 7 to the left and, by means of the wrist pin 11, plate 12 and recess 13, turns the plunger so that the port 3 will register with the inlet 14, and thus at the same time turns the port 4 out of register with the outlet 15; as the cam 5 continues to turn the yoke is raised from the position shown in Fig. 8 and drives the plunger upward, which then causes the lubricant to enter the cylinder; in the next phase of its operation, the cam forces the yoke from the position of Fig. 9 to the right, and, by means of the above-mentioned wrist pin, plate and recess, the plunger is again turned. The plunger is now turned so that the port 4 will register with the outlet 15, and the port 3 is turned so as to be out of register with the inlet. In the next and last phase, the cam forces the yoke downward from the position shown in Fig. 10, and during this move-

ment the yoke drives the plunger on its downward stroke thereby expelling the lubricant from the cylinder through the outlet.

5 I declare that what I claim is:—

1. A pump, comprising a plunger and cylinder formed with distributing ports and passages therein, a yoke adapted to communicate movement to said plunger, means 10 for communicating an intermittent up and down and also a lateral reciprocatory movement to said yoke and means connecting the said yoke with the plunger, whereby the plunger shall also receive a four part movement.
- 15 2. A pump, comprising a plurality of plungers and cylinders formed with distributing ports and passages therein, a yoke connecting together and controlling the said 20 plungers, a cam for communicating an intermittent up and down and also a lateral reciprocating movement to said yoke, and means connecting the said yoke and plungers, whereby the plungers shall also 25 receive a four part movement.
3. A pump, comprising a plurality of plungers and cylinders formed with distributing ports and passages therein, a yoke connecting together and operating said 30 plungers, a quadratic aperture in the yoke, a cam operating in said aperture and adapted to communicate an intermittent up and

down and also a reciprocatory movement to said yoke, and means connecting the said yoke to the plungers whereby the plungers 35 shall also receive a four part movement.

4. A pump, comprising a plurality of plungers and cylinders formed with distributing ports and passages therein, a yoke connecting together and operating said 40 plungers, a quadratic aperture in the yoke, a cam operating in said aperture and adapted to communicate an intermittent up and down and also a reciprocatory movement thereto, and slots in said yoke for permitting 45 lateral movement thereof.

5. A pump, comprising a plurality of plungers and cylinders formed with distributing ports and passages therein, a yoke connecting together and operating said 50 plungers, a quadratic aperture in the yoke, a cam operating in said aperture and adapted to communicate an intermittent up and down and also a reciprocatory movement thereto, and slots in said yoke for permitting 55 lateral movement thereof, and means for communicating a turning movement to the plungers from the yoke.

In testimony whereof I affix my signature, in presence of two witnesses.

ADOLF SELLIN.
